(57) **CLAIM**

The ornamental design for a stretchable sport sock beverage holder, as shown and described.

DESCRIPTION

FIG. 1 is a front, top perspective view of a stretchable sport sock beverage holder showing my new design;

FIG. 2 is a front elevational view thereof, the rear elevational view being identical thereto;

FIG. 3 is a left side elevational view thereof, the right side elevational view being identical thereto;

FIG. 4 is a top plan view thereof; and,

FIG. 5 is a bottom plan view thereof.

The four wavy broken lines shown in the stretchable sport sock beverage holder represent thread stitching. The broken lines illustrating the top oval shape and the circle on the bottom of the stretchable sport beverage holder form no part of the claimed design.
